COMBINATION TOOTH BRUSH AND TUMBLER HOLDER

John F. Bonistall, Zanesville, Ohio

Application May 15, 1958, Serial No. 50,913

Term of patent 14 years

(Cl. D4—3)

FIG. 1

Fig. 1 is a front perspective view of a combination tooth brush and tumbler holder showing my new design; Fig. 2 is a rear perspective view thereof; and

Fig. 3 is a vertical sectional view taken on the line 3—3 of Fig. 2.

I claim:

The ornamental design for a combination tooth brush and tumbler holder, as shown.
